STEPPING RELAY ACCUMULATOR

Reynold B. Johnson, Palo Alto, Calif., assignor to International Business Machines Corporation, New York, N. Y., a corporation of New York

Application July 5, 1952, Serial No. 297,355

7 Claims. (Cl. 235—61)

This invention relates in general to accumulating devices and in particular to a wire contact relay counter.

The principal object of the invention is to provide an inexpensive digital type accumulator capable of operating at higher speeds than prior art accumulators of this type.

Another object of the invention is to provide a high speed, low cost, light weight counter contained within the frame of a wire contact relay of the type disclosed in U. S. Patent No. 2,282,066 of C. D. Lake et al., issued May 5, 1942.

A further object of the invention is to provide a wire contact relay counter having a rotary counter shaft mounted on its armature.

A still further object of the invention is to provide a wire contact relay counter having a rotary counter shaft mounted on its armature and so designed as to enable a decimal notation to be read out according to the binary system.

A still further object of the invention is to provide a wire contact relay counter having an eccentrically shaped rotary counter shaft which is adapted to facilitate the reading out of a factor entered in the counter pursuant to the decimal system.

Other objects of the invention will be pointed out in the following description and claims and illustrated in the accompanying drawings, which disclose, by way of examples, the principle of the invention and the best mode, which has been contemplated, of applying that principle.

In the drawings:

Fig. 1 is a side view of the decimal readout wire contact relay counter shown in a de-energized position.

Fig. 2 is a view showing the eccentrically shaped interposer shaft.

Fig. 3 is a sectional view taken along the lines 3—3 of Fig. 2.

Fig. 4 is a side view of the binary readout wire contact relay counter.

Fig. 5 is a view partly in section and partly broken away of the rotary drum shaft.

Fig. 6 is a sectional view taken along the lines 6—6 of Fig. 5 and showing the disposition of the code bars carried by the rotary drum shaft.

Fig. 7 is a detail view of the code bars.

Figs. 8a and 8b constitute a wiring diagram.

Fig. 9 is a timing diagram.

The relay accumulator is contained in a U-shaped frame 20 (Fig. 1) of insulating material. Within the frame 20 is mounted the yoke 21 to which is fixed a magnet coil 22 and core 23. A pair of screws 24, one at the top and one at the bottom of the frame, serve to hold the yoke in position. A flat armature 25 is pivoted against the upper face of the yoke 21, and confined by the configuration of the frame 20 and the yoke 21 in the manner as described in U. S. Patent No. 2,510,604, issued June 6, 1950 to W. Pfaff et al. Two compression springs 26, only one of which is shown, contained in sockets in the frame 20, press the armature 25 against the face of

2

the yoke 21 thus causing it to rock about the bevelled edge 21a of the yoke as a pivot when the relay is operated. There is also provided the spring 48 which pushes the insulating cap 48a against the armature 25 causing the armature to be normally biased away from the core 23.

There is secured to the armature 25 an armature frame 33 which provides a pivotable support for a rotary counter shaft assembly consisting of a ratchet wheel 34 and an eccentrically shaped interposer shaft 35. The shaft 35 is supported by and rotatably mounted between the insulating hubs 36 and 37 (Fig. 2) which are rotatably supported by the frame 33.

The interposer shaft 35 which is a formed wire comprises ten individual eccentric segments which may be divided into five groups of two each. The two segments forming a group are offset from each other by 180° while adjacent groups are offset by 36° from each other. This shaft, as shall be pointed out subsequently, is advanced 15 in a counterclockwise direction (Fig. 1) in 36° steps so that one group of the eccentric segments will always be in a vertical position (Fig. 2). The upper segment (Fig. 2) when in a vertical position will engage the corresponding wire contact 30 while the lower segment 20 will slightly clear the insulating bar 38. Thus it is to be noted that this disposition of oppositely disposed segments of a particular group tends to prevent deflection of the shaft under the load of the wire contact 30. The segments of the interposer shaft as shown in Figs. 2 and 25 3 have been numbered to correspond to the value to be read out when the segment is in contact with its corresponding wire contact 30.

The left-hand (Fig. 2) outside bend of the wire shaft 35 is contained in the slot 39 of the hub 36 and confined 35 in position by the common contact ring 40. The right-hand outside bend of the wire shaft 35 is contained in the slot 41 of the hub 37 wherein it is fastened. The slot 39 in the hub 36 imparts the torque required to drive the wire shaft 35 while the slot 41 in the hub 37 imparts the torque required to rotate the hub 37 in the bearing fastened to the frame 33.

A ten toothed ratchet wheel 34 is secured to the hub 36 as shown in Fig. 2 which is adapted to cooperate with a pair of pawls 43 and 44.

The pawls 43 and 44 are rotatably mounted on separate studs 45 and 46 both of which are secured to the frame 20. The respective toothed portions 43a and 44a of the pawls 43 and 44 engage the ratchet wheel 34 under the influence of the spring 47. When the armature 25 is attracted by the energization of the magnet coil 22, the engagement of the pawl 43 with a tooth of the ratchet 34 will cause the ratchet 34 and interposer shaft 35 to rotate in a counterclockwise (Fig. 1) direction for approximately 18° or $\frac{1}{20}$ of a revolution. As the ratchet 34 is rotated in a counterclockwise direction, the pawl 44 will ride over a ratchet tooth and engage in the succeeding tooth. As the armature 25 is restored to its normal or de-energized position by the joint action of the spring 26 and the compression spring 48, the ratchet 34 and shaft 35 continue to rotate in a counterclockwise direction being driven by the pawl 44 while the pawl 43 rides over a tooth to engage the ratchet in preparation for the succeeding magnet energization. When the armature is returned to its normal position, the action of the pawl 44 causes the ratchet 34 to rotate another 18° or $\frac{1}{20}$ of a revolution. Thus, the total travel of the ratchet is $\frac{1}{10}$ of a revolution for each electrical impulse received by the coil 22; that is, $\frac{1}{20}$ revolution in attracting the armature 20 plus $\frac{1}{20}$ revolution in releasing the armature. Obviously, each time the ratchet is moved $\frac{1}{10}$ of a revolution, the shaft 35 will be correspondingly rotated.

two units, the raised portions 58 and 60 of the 2 code bar will engage the corresponding common (c) and 2 wire contacts 30; when the ratchet 34 is moved three units, the single raised portion 61 of the 3 code bar 52 will jointly engage the corresponding common, 1 and 2 wire contacts 30; when the ratchet 34 is moved four units, the raised portions 62 and 63 of the 4 code bar 52 will jointly engage the corresponding common and 4 wire contacts 30 (such as shown in Fig. 5) to complete a circuit therebetween; when the ratchet 34 is moved five units, the raised portions 64 and 65 of the 5 code bar 52 will engage the common and 1 wire contact 30 and the 4 wire contact 30; when the ratchet 34 has been moved six units, the raised portions 66 and 67 of the 6 code bar 52 will respectively engage the common wire contact 30 and the 2 and 4 wire contacts 52; when the ratchet 34 has been moved seven units, the raised portion 68 of the 7 code bar 52 will jointly engage the common, 1, 2 and 4 wire contacts 30; when the ratchet 34 is moved eight units, the raised portions 69 and 70 of the 8 code bar 52 will respectively engage the common and 8 wire contacts 30; and when the ratchet 34 is moved nine units, the raised portions 71 and 72 of the 9 code bar 52 will respectively engage the common, 1 and 8 wire contacts 30.

In the disposition of the code bars 52 about the periphery of the drum 51, the 4 code bar 52 is positioned directly opposite the 9 code bar 52 and being so disposed is the only code bar having a raised portion, such as 62, which is adapted to jointly engage the carry wire contacts 49 and the common wire contacts 50. For example, when the ratchet wheel 34 is standing in its 9 position, and with a subsequent energization of the coil 22 causing the armature 25 to be attracted thereto, the carry wire contacts 49 and the common wire contacts 50 will be engaged by the raised portion 62 of the 4 code bar 52 to complete a circuit for setting up a carry operation as shall be explained subsequently.

Circuit diagram

The functioning of the decimal readout relay of Fig. 1 shall be described in reference to an assumed problem. Let it be assumed that the value 196 in the card 74 (Fig. 8a) is to be entered and read out of the relays 73U, 73T and 73H, each of which is similar in construction to the relay of Fig. 1.

The record card 74 containing the value 196 is placed in a sensing position between the conductive roll 75 and a set of brush sensing elements 76 of which there is one for each card column being sensed. As usual, the presence of a digit representing perforation in any card column will allow the related brush 76 to make electrical contact with the conductive roll 75. The particular mechanism for feeding record cards and sensing the perforated data therein form no part of the present invention and, accordingly, have been shown in a diagrammatic manner in Fig. 8a. It might be added at this time that in the circuit diagram are shown a number of cam operated contacts, all of which are designated with the prefix CB. The cams for controlling these contacts are all mounted on a common shaft which is caused to rotate continuously and in synchronization with the feeding of the record card through a suitable power source in a well known manner. The timing of the contacts controlled by these cams is shown in Fig. 9 for one machine cycle, and it will be understood that this is repeated.

Each brush 76 is connected to a respective one of the group of relays identified as R1, R2 and R3 which become energized upon the detection of a perforation by the corresponding brush 76. With the energization of the respective relays R1, R2 and R3 at "6", "9" and "1" index time, a hold circuit will be established for these relays by the cam controlled contacts CB1 through the respective a contacts. The circuit established for energizing the relay R2, for example, is traceable as follows: line 77 coupled to a positive source of potential (not shown), cam controlled contacts CB making each index point time as

70
75 (c) and 1 wire contacts 30; when the ratchet 34 is moved

There is embedded in the frame 20 the contactors 27 and 28 with the contactor 28 coupled to the terminal wires (not shown) of the coil 22. Extending through the contactor 27 is a wire contact spring 30 which is adapted to contact the common contact ring 40 when the armature 25 is in its normal or de-energized position such as shown in Fig. 2. The upper end of this wire is hooked as shown in Fig. 1 with the hook extending through a hole 31 in a plate 32. The plate 32 is positioned on the top of the frame 20 and held thereto by the upper screws 24. The plate 32 is adapted to be moved to left or right to decrease or increase the pressure against the upper end of the wire 30. As indicated in Fig. 2, there is provided additional spaced aligned wire contacts 30 which are adapted to be successively engaged by the corresponding numbered segment of the shaft 35 as the shaft 35 is rotated through the stepping of the ratchet 35 caused by the movement of the armature 25. It is to be noted from Fig. 2 that each of the segments of the shaft 35 representative of the digits 0 to 8, inclusive, have a single pair of corresponding wire contacts 30 associated therewith while the 9 segment of the shaft 35 has associated therewith two pairs of wire contacts 30, the purpose of which will be made clearer subsequently in the description of the wiring diagram.

There is also provided two additional pairs of wire contacts 49 and 50 which become effective during a carry operation. For example, when the coil 22 is energized with the 9 segment engaging its corresponding wire contact pair 30, the armature 25 upon being attracted to the coil will cause the left-hand end 35a of the conductive shaft 35 to contact the wire contacts 49 and the common contact ring 40 to engage the wire contacts 50. This operation will enable a carry circuit to be set up in a manner which shall be described subsequently in more detail. There is provided a contactor 27 for each pair of the wire contacts 30, 49 and 50.

It is believed pertinent to mention at this time with reference to Fig. 2 showing the 9 wire contact 30 engaging the corresponding contact, that the electrical circuit established is from the 9 contactor 27, the 9 wire contact 30, the 9 segment of the conductive shaft 35, the common contact ring 40, the corresponding wire contacts 30 and contactor 27.

A modification of the decimal readout electromagnetic relay of Fig. 1 is shown in Fig. 4 wherein the interposer shaft 35 of Fig. 2 has been replaced by a fluted insulating drum 51 having nine code bars 52. The device of Fig. 4 enables digital values to be read out according to a binary code.

The drum 51 is mounted on the shaft 53 which is rotatably supported at the pivots 54 and 55 (Fig. 5) by the frame 33. The nine code bars 52 are disposed about the periphery of the drum at intervals of 36° in a manner such as shown in Fig. 6. It is to be noted from Fig. 7 that no code bar is provided for zero. The code bars 52 are retained and electrically connected by the rings 56 and 57 positioned at extreme ends of the drum 51.

In the binary readout relay only five wire contacts 30 are provided where one of the wire contacts 30 (labeled C in Fig. 5) will engage the common raised portion of each bar, such as 58 of the 2 bar 52, while the other wire contacts 30 respectively representative of the digits 1, 2, 4 and 8 will be engaged either singly or in combination by the appropriate code bars. As in the case of the decimal readout relay, there are also provided wire contacts 49 and 50 which will be engaged by the appropriate code bars when the armature is attracted to the coil during the time when a carry operation is called for.

Fig. 7 shows the raised portions required in each of the code bars 52 to transpose the decimal system into a binary system. For example, when the ratchet 34 is moved one unit, the raised portion 59 of the 1 code bar 52 will be in position to jointly engage the corresponding common

shown in Fig. 9, contacts R4*j* and R27*d* normally closed, conductive roll 75, "9" perforation in record 74, corresponding brush 76, pickup coil of relay R2, and then to conductor 82 coupled to the negative terminal of the source of potential.

The energization of the relay R2 will close the contacts R2*b* at "9" time thereby enabling nine separate pulses to be applied to the relay 73T by the cam controlled contacts CB2 (see Fig. 9 for timing). As previously mentioned, each pulse applied to the relay 73T will cause its ratchet 34 to step such that at "0" index time the 9 segment of the interposer shaft 35 will be in engagement with the corresponding pair of wire contacts 30. Thus as a result the pair of 9 contacts 9*a* and 9*b* (Fig. 8*b*) of the tens order will be closed. It may be pointed out that in the circuit diagram various relays are shown at points remote from the contacts which they control. This has been done to simplify the wiring connections, and to clearly identify related parts the relays have been shown in dotted outline adjacent the contacts they control.

In a similar manner the relays R1 and R3 will be energized respectively at "1" and "6" index time causing the corresponding *b* contacts to close, thereby enabling the relays 73H and 73U to be pulsed 1 and 6 times, respectively. This operation will close the 6 contacts 30 in the units order and the 1 contacts in the hundreds order.

At "0" index time with the contacts 9*b* in the tens order now closed, a circuit will be established with the making of the contacts CB5 and CB7 at this time (see timing diagram of Fig. 9) to condition the tens order for a carry-over operation through the energization of relay R6. This circuit may be traced as follows: conductor 77 (Fig. 8*b*) coupled to the positive terminal of a source of potential (not shown), contacts CB5 now closed, line 78, total relay contacts R4*e* (Fig. 8*b*) as shown, conductor 79, contacts 9*b* of the tens order now closed, conductor 80, pickup coil of relay R6, conductor 81, total relay contacts R4*g* normally closed, contacts CB7 now closed, and then to line 82 coupled to the negative terminal of the source of potential. The circuit just traced will result in the relay R6 being energized and the associated contacts R6*a* (Fig. 8*b*) and R6*b* (Fig. 8*a*) being closed. An obvious hold circuit for relay R6 will be set up by the cam controlled contacts CB4 through the contacts R6*a*. It is pointed out that whenever a "9" is sensed in the units or hundreds order, the corresponding relays R5 and R7 will be similarly energized.

Whenever the associated ratchet wheel of the units, tens, or hundreds order passes from 9 to 0, the associated carry contacts 50 will be closed thus enabling a circuit to be established for energizing the corresponding carry relay R8, R9 or R10 when the cam controlled contacts CB2 make. As an example, the circuit established for energizing the units carry relay R8 is traced as follows: conductor 77, cam controlled contacts CB2 now closed, contacts R4*h* normally closed, conductor 87, units carry contacts 50 now closed, conductor 88, pickup coil of relay R8 and then to the negative conductor 82. An obvious hold circuit for relay R8 will be set up through the contacts R8*a* by the cam controlled contacts CB4.

Now proceeding along the assumption that the units carry relay R8 is energized, when the cam controlled contacts CB3 make as shown in the timing diagram of Fig. 9, a carry operation will take place causing the relay 73T to be pulsed and advanced one unit.

Thus when the contacts CB3 close and with carry relay contacts R8*b* (Fig. 8*a*) now shifted, a circuit will be established for pulsing the next higher order relay. This circuit may be traced from line 77, contacts CB3 now closed, contacts R8*b* now closed, R22*b* normally closed, relay 73T and then to conductor 82. Since relay 73T has standing therein a 9 value causing relay R6 to be energized as previously described, a parallel circuit

from the shifted contacts R8*b* will be set up for pulsing the relay R73H, thereby extending the carry to the next higher order. This circuit is traceable from the shifted contacts R8*b* as follows: contacts R6*b* now closed, R9*b* as shown, R23*b* normally closed, relay 73H and then to conductor 82. Thus under the assumed carry conditions, the relay 73T will be stepped one unit to 0 while the relay 73H will be stepped to the 2 position.

After the amounts in a particular group of cards have been successively accumulated in the associated accumulating devices through the pulsing of the corresponding relays 73U, 73T and 73H, a total printing operation is initiated by the operator closing the total print switch 89. With the switch 89 now closed, the total relay R4 will be energized through an obvious circuit when the cam controlled contacts CB9 close as shown in Fig. 9. A hold circuit is established for relay R4 through the contacts R4*a* by the cam controlled contacts CB8. The energization of relay R4 will enable the value standing in the various orders to be read out during the succeeding cycle. It is pointed out that during this succeeding cycle the contacts R4*j* will be opened to prevent any further entries being made into the accumulators. While it is not any part of this invention, it is obvious that the feeding of cards during a total print cycle may be halted in a well known manner.

A description of the manner of reading out the units order, for example, will now be set forth. It is recalled that the 6 contacts in the units order is closed. Thus when the cam controlled contacts CB6 close at "6" index time and with the brush 83 contacting the 6 segment of the emitter 84, a circuit will be established for reading out the value 6. This circuit is traced as follows: line 35 77 (Fig. 8*b*), contacts CB6 and R4*c* now closed, 6 segment of the emitter 84, 6 contacts 30 of units order now closed, conductor 85, contacts R4*f* now shifted, magnet 86, and then to conductor 82. As is well known, the energization of magnet 86 will control the usual recording devices, such as punching or printing, in a well known manner. It is to be realized that concurrently with the reading out of the units order the remaining orders are likewise being read out.

After the printing or punching of the total, as the case 45 may be, has been taken, the restoring of the counters to 0 position will be brought about by the closing of the restoring key 90 which will cause the restoring relays R21, R22, R23 and R27 to pick up when the cam controlled contacts CB11 close as shown in the timing diagram of Fig. 9. A holding circuit for relays R21, R22 and R23 will be set up through its associated *a* contacts and the corresponding zero relay contacts R24*b*, R25*b* and R26*b*. A holding circuit for relay R27 will be set up through the now closed contacts R27*a* and any one 55 of the contacts R21*c*, R22*c* and R23*c*. The energization of relay R27 will close contacts R27*b* (Fig. 8*a*) to prevent the taking of a total and R27*d* (Fig. 8*a*) to prevent the entering of data during a restoration operation.

The energization of the relays R21, R22 and R23 will 60 transfer the associated contacts R21*b*, R22*b* and R23*b* (Fig. 8*a*) thereby enabling a series of CB2 impulses to be applied to the magnet coils 73U, 73T and 73H. The series of CB2 impulses will advance the respective counters to zero. When a counter reaches the zero position, the 0 contact 30 (Fig. 8*b*) will close picking up the corresponding zero relays R24, R25, and R26, as the case may be, through a circuit established when the cam controlled contacts CB6 make. As an example, the circuit established for energizing the zero relay R24 of the units order 65 is traceable as follows: conductor 77, contacts CB6 now closed, R27*c* now closed, 0 contacts 30 now closed, conductor 91, relay R24 and then to the negative conductor 82. As each of the zero relays R24, R25 and R26 become energized, the associated contacts R24*b*, R25*b* and R26*b* open to break the hold circuits of the correspond-

ing restoring relays R21, R22 and R23 thereby enabling the respective counters to remain at the now assumed zero position.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a device of the class described, a coil, an armature, a yoke for said coil, a supporting frame pivotably supporting said armature, a plurality of wire contacts arranged in parallel alignment and having one end secured by said frame, each of said contacts representative of a different digit, a rotary counter shaft having conductive elements respectively representative of the digits 1, 2, 3, 4, 5, 6, 7, 8 and 9, ratchet means secured to said shaft, said ratchet means and said shaft being rotatably carried by said armature, the alignment of said contacts being in parallel with the longitudinal axis of said shaft, pawl means for stepping said ratchet, said pawl means being secured to said frame, said pawl means causing said ratchet to be stepped each time said armature is attracted to said coil and restored to its normal position, said conductive elements successively contacting said wire contacts as said ratchet is stepped.

2. A device such as claimed in claim 1 wherein said rotary counter shaft comprises a formed wire having ten individual eccentric segments, said segments being divided in five groups of two each, said segments within a group being offset from each other by 180° while adjacent ones of said segments are offset 36° from each other.

3. A device such as claimed in claim 2 wherein said rotary counter shaft comprises drum means having circumferentially disposed a plurality of code bars, said code bars effecting selection of certain of the wire contacts pursuant to the binary system during the stepping of said ratchet.

4. In a device of the class described, a coil, an armature pivotably supported with respect to said coil, a counter shaft, ratchet means secured to said shaft, said shaft being rotatably supported by said armature, said shaft comprising a formed wire having a plurality of individual numerically valued conductive eccentric segments, a plurality of contacts each having one free end arranged to engage the corresponding one of said conductive segments as said ratchet steps said shaft, pawl means, said pawl means causing said ratchet to be moved one unit when said armature is attracted to said coil and restored to its normal position.

5. In a device of the class described, a coil, an armature pivotably supported with respect to said coil, a

counter shaft, ratchet means secured to said shaft, said shaft being rotatably supported by said armature, said shaft comprising drum means having circumferentially disposed a plurality of code bars, a plurality of contacts respectively representative of the digits 1, 2, 4 and 8, means for successively feeding a number of pulses representative of a decimal value to said coil, pawl means, said pawl means causing said ratchet to step said drum means one unit for each of said pulses, said code bars being so arranged to engage said contacts either singly or in combination for converting said decimal value to the binary system.

6. In a device of the class described, drum means having a plurality of elongated bars circumferentially disposed and respectively representative of the digits 1, 2, 3, 4, 5, 6, 7, 8 and 9, a plurality of contacts respectively representative of the digits 1, 2, 4, 8, carry contact means, said bars each having projections adapted to contact said contacts either singly or in combination as said drum means is rotated in a step-like manner, said bar representative of the 4 digit having an additional projection for engaging said carry contact means as said drum means is stepped from a 9 position to a 0 position, and means for stepping said drum through nine positions respectively designated as 1, 2, 3, 4, 5, 6, 7, 8 and 9.

7. In a device of the class described, relay means including an armature, shaft means having ten rotative positions, said shaft means having a number of eccentric conductive segments equal to said positions, a common contact ring engaging one end of said shaft, said shaft means rotatably supported by said armature, means upon energizing said relay means for causing said shaft to be stepped through said positions, a plurality of contact means, there being at least one of said contact means corresponding to each of said segments, an additional contact means for engaging said ring as said shaft is stepped from the first to the last of said positions, each of said contact means engaging the corresponding one of said segments as said shaft is stepped through said positions, and additional contact means for respectively engaging said ring and said shaft during the interval as said shaft is stepped from the last to the first of said positions.
